UNITED STATES PATENT OFFICE.

GEORGE V. RASMUSSEN, OF NEW YORK, N. Y.

AUTOMATIC VACUUM-CLEANER.

1,275,747.

Specification of Letters Patent. Patented Aug. 13, 1918.

Application filed February 16, 1911. Serial No. 609,007.

To all whom it may concern:

Be it known that I, GEORGE V. RASMUSSEN, a citizen of the United States, and resident of the city of New York, county of Richmond, and State of New York, have invented certain new and useful Improvements in Automatic Vacuum-Cleaners, of which the following is a specification.

My invention relates to vacuum cleaners, or sweepers as they are sometimes called. More particularly my invention relates to a type of vacuum cleaner in which the cleansing tool and the suction producing mechanism is incorporated into a single compact and organized structure which is moved as a whole over the floor or surface to be cleaned with the cleansing tool in contact with said surface the suction being automatically produced by virtue and in consequence of such movement. I therefore provide a manually operated cleaner which requires but one person for its operation.

The object of my invention is to provide a cleaner as aforesaid, which can be guided and operated by one person, which requires no power other than that expended by the operator as he moves it over the floor, which holds the cleaning tool proper with constant pressure and at a suitable, preferably constant, angle to the surface which is being cleaned while at the same time providing adjustment for any inequalities in said surface, and which provides further a uniform, continuous and ample suction for the purposes intended. A further object of my invention is to provide a cleaner as aforesaid of simple construction with all parts easily and quickly accessible, and of durable construction. Other objects will appear as the specification proceeds.

In the drawings Figure 1 represents a side elevation of a preferred form of cleaner made according to my invention; Fig. 2 represents the same in rear elevation; Fig. 3 represents a central longitudinal section taken along the line 3—3 of Fig. 2; and Fig. 4 is a plan view from above of the same cleaner.

Referring to the drawings, a main casing 1 of wood or sheet metal is carried upon a system of four wheels 2 arranged in pairs, and provided with a yoke 3, pivotally attached to the casing, having a handle 4. Arranged oppositely to one another within the casing are fixed members 5 and 5' of two bellows 6 and 6', these members extend-

ing substantially clear across the casing and forming with the sides and bottom of said casing a rectangular suction chamber 7; a cover 8 having attached thereto a dust bag 9 closes the suction chamber above. Downwardly convexed leaf-springs 10 and 11 pivoted to the casing at 12 and adapted to be swung down over said cover so as to be fastened in position by catches 13 are provided to hold this cover in position; leaf-spring 11 has riveted to its under side a subcover 14 adapted to engage snugly a suitable opening in cover 8 and giving access to the interior of the dust bag.

An inlet fixture 15, hollowed below to correspond with an opening in the cover 8, is fixed to the top of said cover and provided with a nozzle 16 over which is slipped a piece of flexible rubber tubing 17 the other end of said tubing being engaged with the end of the tube 18 which carries at its extremity the cleaning tool proper 19. Tube 18 is carried upon the front end of casing 1 by two brackets 20 and 21 carrying co-axial bearings 20', 21', the latter being set somewhat in advance of the former, in which tube 18 is slidably held. An adjustable screw nut 22 fixed to tube 18 a little above bearing 21' forms an abutment between which and bracket 20' is fitted a spiral spring 23 which operates to press tube 18 downwardly until stopped by a second adjustable nut 24 abutting against the top of upper bracket 20'. By means of the two nuts 22 and 24 the pressure with which the cleaning tool 19 engages the surface to be cleaned may be adjusted.

Each bellows 6 and 6' is provided with a movable member 25 and 25' connected by a link 26, 26' to a crank 27, 27' formed at the center of the two axles joining the two pairs of wheels and to which the wheels are rigidly fixed. Each axle is rotatably supported in bearings 28, 28' attached to the inclined front and back of casing 1.

Opposite ends of each axle just within the wheels 2 are provided with oppositely turned cranks 29, 29', the cranks belonging to wheels on each side of the case being joined by links 30. The central cranks 27, 27' are set, with reference to one another, at an angle of 90° so that when one bellows is fully expanded the other is fully closed and vice versa, the bellows being operated alternately.

Both the fixed and movable member of

each bellows is provided with flap valves 31 in the usual way, so that as each bellows opens air is drawn up through the cleaning tool 19 the tubes 18, 17 and the fixture 15 5 through the dust bag 9 into said bellows, and as the bellows closes said volume of air is passed out through the movable member into the atmosphere.

To prevent the suction from either bellows drawing up the dust bag 9 against the fixed member of said bellows so as to stop off the opening of its flap valve I prefer to attach a stiff rectangular bottom 32 to the lower end of said dust bag and to said bottom 15 a pair of longitudinally arranged strips 33 extending over nearly the entire space between the bellows members 5 and 5' which form the opposite sides of suction chamber 7. This bottom and strips also serve to 20 keep the dust bag fully extended and distended and from becoming twisted in any way in the suction chamber.

The cleaning tool 19 has swiveled engagement with the tube 18 and is joined, near 25 opposite ends, to the casing 1 by spiral springs 34.

In operation my improved cleaner is simply moved forward and backward, or either forward or backward, the direction of movement being immaterial, by means of the handle 4 over the surface to be cleaned; should the cleaning tool 19 press against 30 said surface with too much or too little pressure a turn or two given to the adjustable nuts 22 and 24 will enable the desired quality of engagement to be quickly secured. As this movement takes place the wheels 2 are revolved as one system turning the two axles to which they are fixed and alternately 35 operating the bellows 6 and 6' through the central cranks 27, 27' and links 26, 26' so as to produce a substantially continuous suction in the suction chamber 7 resulting in a continuous inrush of dust laden air into 40 and through the dust bag 9 the dust remaining behind within said bag.

Should the cleaning tool 19 meet with an obstruction as to either end while my cleaner is being operated the tool will turn pivotally 45 upon the tube 18 against the resistance of the springs 34 but will be instantly restored to position when the obstruction is removed. This condition is most likely to take place when the cleaner is run too close to a wainscoting or piece of furniture and at an angle.

Cleaning tools of any desired type may readily be substituted for the tool shown in the drawings by disengaging the springs 34, any known type of removable swivel 50 joint being employed for holding the cleaning tool in place.

To remove the dust and clean out the dust bag it is only necessary to lift the two leaf springs 10 and 11 and remove the bag 55 by lifting away the cover 8; the dust and

dirt may then be dumped out through the opening uncovered by a sub-cover 14.

When the cleaner is not in use the handle 4 may be removed from fork 3.

The cleaner of my invention is simple and 70 compact, has no delicately adjusted parts to get out of order and is effective when made in sizes capable of being run under tables and many articles of furniture. It will furnish ample suction when moved over a 75 surface to be cleaned at speeds approximately those used with known suction cleaning tools connected with stationary or other suction apparatus. There being but few bearings these may be made of the most 80 approved type without materially adding to the cost of construction so that most of the power required to operate the cleaner goes to the working of the bellows and the production of suction.

Having described my invention, I claim:

1. In a vacuum cleaner the combination of a casing provided with a suction chamber, wheels supporting said casing, a cleaning tool carried by said casing and adapted to 90 be turned with respect thereto about an upright axis, springs for resisting said turning movement, a suction pump attached to said casing, a dust bag within the suction chamber between the cleaning tool and the 95 suction pump and means connected with the wheels and the suction pump for operating said pump.

2. In a vacuum cleaner of the class described the combination of a casing, a cleaning tool carried by said casing and rotatably and vertically movable relatively thereto, resilient means for pressing said tool downwardly and resilient means for resisting a 100 rotative movement thereof.

3. In a vacuum cleaner of the class described the combination of a bracket, a cleaning tool slidably and pivotally supported by said bracket, springs engaging said bracket and said tool for pressing the latter downward, and springs engaged with said tool for resisting its pivotal movement.

4. In a vacuum cleaner of the class described the combination of a pivotally and slidably supported cleaning tool adapted to 115 move up and down, yielding means for pressing said tool downward, and yielding means for resisting pivotal movement.

5. In a vacuum cleaner of the class described the combination of a pivotally and 120 slidably supported cleaning tool adapted to move up and down, and yielding means for pressing said tool downward, said downwardly acting yielding means being adjustable as to the force it exerts.

6. In a vacuum cleaner, the combination of a casing carried upon wheels and provided with a suction chamber, a cleaning tool carried by said casing and adapted to turn about an upright axis, yielding means 125

for resisting said turning movement, and a suction pump operatively connected with said wheels for drawing air through the cleaning tool to the suction chamber.

5 7. In a vacuum cleaner, a support, a cleaning tool movably carried thereby, means for positioning said tool at varying distances from the surface on which said tool is operating and a spring exerting a 10 downward pressure on said tool.

8. In a vacuum cleaner a support, a cleaning tool movably carried thereby, means for positioning said tool at varying distances

from the surface on which said tool is operating, a spring exerting a downward pressure on said tool and means for adjusting the tension of said spring to vary the degree of pressure upon said tool. 15

In testimony whereof I have hereunto set my hand in the presence of two subscribing 20 witnesses.

GEORGE V. RASMUSSEN.
